(57) **CLAIM**

The ornamental design for a condensate drain line water proof sensor, as shown and described.

DESCRIPTION

FIG. 1 is a front isometric view of the showing the condensate drain line water proof sensor design;

FIG. 2 is front view thereof;

FIG. 3 is a back view thereof;

FIG. 4 is a right view thereof;

FIG. 5 is a left view thereof;

FIG. 6 is a top view thereof;

FIG. 7 is a bottom view thereof;

FIG. 8 is an isometric view of the condensate drain line water proof sensor shown in a configuration of use;

FIG. 9 is front view thereof;

FIG. 10 is a back view thereof;

FIG. 11 is a right view thereof;

FIG. 12 is a left view thereof;

FIG. 13 is a top view thereof;

FIG. 14 is a bottom view thereof; and,

FIG. 15 is an exploded, perspective view shown in a configuration of use showing the invention.

The broken line showing of a t-fitting is included for the purpose of illustrating unclaimed environment and forms no part of the claimed design.
